(57) CLAIM

What is claimed is the ornamental design for a two tier fruit server, as shown and described.

DESCRIPTION

FIG. 1 is a perspective view of a two tier fruit server showing a new design;

FIG. 2 is a front view of the two tier fruit server of FIG. 1;
FIG. 3 is a rear view of the two tier fruit server of FIG. 1;
FIG. 4 is a side view of the two tier fruit server of FIG. 1;
FIG. 5 is a top view of the two tier fruit server of FIG. 1; and,
FIG. 6 is a bottom view of the two tier fruit server of FIG.

The components of the display shown in broken lines illustrate portions of the two tier fruit server form no part of the claimed design.
